UNITED STATES PATENT OFFICE.

ARTHUR E. MCCLAIN, OF GREENFIELD, OHIO, ASSIGNOR TO THE AMERICAN PAD & TEXTILE COMPANY, OF GREENFIELD, OHIO, A CORPORATION OF OHIO.

PAD-STUFFING MACHINE.

1,112,545.

Specification of Letters Patent.

Patented Oct. 6, 1914.

Application filed February 24, 1912. Serial No. 679,670.

To all whom it may concern:

Be it known that I, ARTHUR E. MCCLAIN, a citizen of the United States of America, and resident of Greenfield, county of Highland, and State of Ohio, have invented certain new and useful Improvements in Pad-Stuffing Machines, of which the following is a specification.

This invention relates to pad stuffing machines and is an improvement on machines similar to those disclosed in the patent to Brownson *et al.* No. 976,982, of November 29, 1910.

An object of my invention is to produce a machine which will stuff a relatively long pad, such as a sweat pad for horses, from one end to the other in one continuous operation.

A further object is to produce a stuffing machine in which means are employed for varying the packing pressure during the stuffing operation and for thereby varying the degree of compactness of the padding material at points along the pad.

These and other objects I attain in a machine embodying the features herein illustrated and described.

In the drawings accompanying and forming a part of this application Figure 1 is a plan view of a machine embodying my invention, the cover of a sweat pad being shown in place on the machine and being partially broken away for convenience of illustration. Fig. 2 is a side elevation of the machine illustrated in Fig. 1. Fig. 3 is a fragmental perspective view of a tubular conveyer, shown in connection with a fragment of a pad cover and means for holding the cover in the proper position relatively to the conveyer. Fig. 4 is a fragmental perspective view of a plunger which forms a detail of the machine illustrated and is normally located within the tubular conveyer illustrated in Fig. 3. Figs. 5 and 6 are respectively, elevations of the conveyer end, and the driving shaft end, of the machine illustrated. Fig. 7 is a view of a pad cover such as is adapted to be employed in making sweat pads for horses and of being stuffed with padding material by a machine embodying my invention.

The machine illustrated is adapted to completely fill the cover of a relatively long pad, with padding material in one continuous operation and without the necessity of

disengaging the cover from the machine after it has been half filled and of turning it so that the remaining portion can be filled, as is the case with the machine illustrated in the Brownson patent, to which reference has been made. Such a procedure consumes time, but the principal objection to it is that it necessitates providing an aperture midway between the ends of the pad cover, into which the conveyer is inserted during the stuffing operation. It is difficult to secure the edges of such an aperture together, after the pad is stuffed, and they must either be sewed by hand or by means of complicated and expensive machines. These difficulties are overcome in a machine embodying my invention since each machine is so arranged that the padding material is introduced into each pad cover through an opening formed in one end of the cover and means are provided for holding the pad cover in place so that it may be stuffed, from end to end, in one continuous operation. In addition to this my invention provides means for varying the packing pressure during the stuffing operation so that the compactness of the padding material in the pad may be varied at points along the pad. I preferably decrease the packing pressure at a point midway between the ends of the cover, or at the point of maximum curvature of the pad while it is in use, so that a minimum amount of padding material will be located at that point and the pad may be readily bent to conform to the curvature of the horse collar.

The machine illustrated, is in some respects similar to the machine disclosed by the Brownson patent and includes a frame portion 8, a tubular conveyer 9, a hopper 10, which communicates with the conveyer 9, and a rotatable impeller 11 which conveys padding material, introduced into a conduit 12, with which the hopper is provided, through the hopper 10 and into the conveyer 9. A plunger 13 is located in the conveyer and is actuated by means of a crank disk 16, through the agency of a cross head 14 and a connecting rod 15. The disk 16 is mounted on a driving shaft 17 which is located at the opposite end of the machine from the conveyer. The plunger 13 and the conveyer 9 are similar to the plunger and conveyer of the Brownson patent and are provided with teeth similar to those de-

scribed in the patent, and so arranged that they coöperate to move the packing material forward through the conveyer during the reciprocations of the plunger.

5 The hopper 10 and the impeller 11 are similar to those illustrated in the patent and the impeller is driven by means of a pulley 18, mounted on the driving shaft 17 through the agency of a belt 18'. Any suitable means 10 may be employed for transmitting power to the driving shaft of the machine, but I have illustrated a belt drive, similar to that disclosed in the patent, which consists of a loose and a fixed pulley, mounted on the driving 15 shaft 17, and means for shifting a belt 19 from one pulley to the other, when it is desired to start or stop the machine.

During the operation of stuffing a pad, a pad cover P is inserted over the end of the 20 conveyer 9 and is held in place so that it is capable of being moved relatively along the conveyer by the padding material as it is stuffed into place by the plunger. With my invention I provide an opening in one end 25 of the pad cover to be stuffed, such as is illustrated at 21 in Fig. 7, and I then move the cover to position on the machine by inserting the end of the conveyer through the opening. I have illustrated two sets of 30 clamps for holding the cover in place over the conveyer during the stuffing operation, which are so arranged that one set is effective, both in holding the cover in place and in controlling the packing pressure under which the padding material is introduced into the cover, during a portion of the 35 stuffing operation and then the other set of clamps is rendered effective in performing these functions after the first set has been 40 rendered inoperative. The clamps 22 form one set and are normally adapted to engage the opposite sides of a cover to be packed at points about midway between its ends. The clamps 23 form the other set and are adapted 45 to engage the opposite sides of a cover at points immediately adjacent to its open end.

Each clamp 22 is shown mounted on a rod 24, which extends longitudinally of the machine and is mounted in ways, provided 50 through which it is capable of moving longitudinally. A weight 25 is suspended from the rear end of each rod 24 by means of a cord or similar member which extends over a pulley 26 mounted on the frame 55 8 of the machine. A spring 27 is provided for each clamp 22 and is so arranged that it normally holds the clamp in the clamping position. The movable jaw of each clamp is provided with a downwardly extending arm 60 on which a laterally projecting extension 28 is mounted. Each projection is adapted to move the jaw to disengage the clamp from a pad cover, when it is moved into engagement with a stop 30, during the stuffing operation, as will hereinafter be described.

Each clamp 23 is mounted on a rod 31 which extends longitudinally of the machine and is mounted in ways through which it is capable of moving longitudinally. A weight 32 is suspended from the rear end of each 70 rod 31 by means of a cord, or similar suspending member, which extends over a pulley 33 mounted on the frame 8. The clamps 23 like the clamps 22, are provided with springs for normally holding them in the 75 clamping position and the movable jaw of each clamp 23 is shown provided with an upwardly projecting inclined finger 23' which is easily accessible to the operator of the machine and which may be readily depressed to spread the jaws apart for the purpose of introducing a cover into the clamp 80 or disengaging one from it.

The rods 24 and 31 are provided with stops which may be moved to different positions for the purpose of adjusting the normal positions of the clamps 22 and 23. In the drawings I have illustrated these stops as screw bolts or nuts 40 which are adapted to be screwed into apertures suitably spaced 90 along the rods. The pull of the weight secured to each rod normally holds the rod so that the stop 40 mounted on it is held against an abutment 42 which also forms one of the ways for guiding the rods in their 95 motion.

The stops 40 are so located on the rods 24 that a cover P will be held fairly tight over the end of the conveyer when its edges are held, as above described, by the clamps 22. 100 The stops on the rods 31 are so adjusted that the cover P will not be held tight by the clamps 23 until after it is half filled with padding material and the clamps 22 have been disengaged from it. In other words, 105 the clamps 23 are normally so located that they will not resist the forward motion of the cover, occasioned by the stuffing operation, until after the clamps 22 have been disengaged from the cover.

110 The operation of filling a cover is in some respects similar to that described in the Brownson patent. After the cover P is in place on the conveyer and the clamps 22 and 23 are adjusted, the driving belt 19 is shifted 115 to the fixed pulley on the driving shaft 17 so that it reciprocates the plunger 13 through the agency of the connecting rod 15 and cross head 14 and drives the impeller 11 120 through the agency of the pulley 18 and the belt connection. The impeller delivers the padding material from the hopper to the conveyer 9, and the plunger 13 moves the padding material through the conveyer and packs it into the cover. As the cover is 125 filled with the material it is moved along the conveyer by the plunger as it forces the material through the conveyer. This motion is, however, resisted by the weights 25, secured to the rods 24 and consequently the compres- 130

sion or packing pressure of the padding material in the cover is controlled by the weights, as is set forth in the Brownson patent.

5 The stops 30 are mounted on a bracket, secured to the frame 8 of the machine, so that they engage the extensions 28 formed on the downwardly projecting arms of the clamps 22, as the clamps 22 are moved forward by 70 the cover. The stops are so located that they actuate the clamps to disengage them from the cover when the cover is substantially half full of padding material. As soon as the clamps 22 are disengaged they 75 are moved back to the normal position by means of their weights 25.

During the operation of stuffing the first half of a cover P the clamps 23 remain stationary and do not resist the forward motion 20 of the front part of the cover, since the cover is loosely folded or is slack between them and the clamps 22 and, while the slack is gradually taken up as the clamps 22 move forward, the normal position of the clamps 23 25 is such, that the cover does not exert a pull on them until after the clamps 22 have been disengaged from the cover as has been described. The clamps 23 then resist the forward motion of the cover during the remainder of the stuffing operation and they 30 therefore control the stuffing pressure, that is, the degree of compactness of the padding material in the pad.

I have found it desirable to decrease the 35 packing pressure, or the degree of compactness of the padding material within the cover at a point about midway between the ends of the pad. I accomplish this by adjusting the position of the weights 32 so 40 that they will not resist the forward motion of the clamps 23 until after the clamps have been moved forward a determined amount by the forward motion of the cover. The amount of this motion is determined by the 45 amount of loose packing desirable in each pad.

In the machine illustrated I adjust the 50 position of the weights by providing a rest, or support 44 for the weights 32 which is capable of being secured in different positions along an upright 45, which forms a portion of the frame 8 of the machine. The support 44, illustrated, is provided with bolts 46 or similar devices which extend 55 through a slot provided in the upright and are capable of securing the support in different positions along the upright. With this arrangement the support 44 may be so adjusted that the rods 31 will be relieved of 60 the pull of the weights until after the clamps 23 have moved forward a sufficient amount to insure the desired amount of loose packing in the pad. The weights 32 are the same size as the weights 25 and consequently they 65 will resist the forward motion of the cover

P to the same extent as the weights 25 and the same packing pressure will therefore be obtained in each end of the pad. It will be understood that, if desired, different sized weights may be employed to vary the packing pressure, that is, the degree of compactness of the padding material throughout the length of the pad, and that means other than weights may be employed for yieldingly restraining the forward motion of the clamps. 75

After the central portion of the cover has been stuffed the further forward motion of the cover is resisted by the weights 32 as the rods 31 move forward. The stuffing operation is continued until the cover is completely filled with padding material at which time a stop 34, carried by one of the rods 31 moves into contact with a releasing lever 35, similar to the release 43 shown in the Brownson patent, and thereby actuates a 80 lever 36, which releases a finger 37, carried by a shaft 38 and permits the belt shifter fork 39 to move in response to the pull of a suspended weight 40' and to shift the belt 19 to the loose pulley. This stops the plunger 90 and the impeller and consequently stops the delivery of padding material through the conveyer. The apparatus just described is similar in operation to the automatic belt shifting apparatus described in the above 95 referred to patent and a further description of it is deemed unnecessary.

The stuffed cover may be released from the machine by depressing the upwardly projecting arms of the clamps 23. The edges of 100 the apertures in the end of the pad cover can then be sewed together to complete the pad. This sewing operation is comparatively simple and can be quickly and cheaply performed with an ordinary sewing machine. When the clamps 23 are released 105 they are drawn back to the normal or starting position by their weights 32 and the machine is ready to receive another cover P to be stuffed. 110

The machine illustrated simplifies and cheapens the process of manufacturing pads and I wish it to be understood that while I have illustrated the preferred form of the machine and described its parts and the 115 principles of its operations that various changes, modifications and substitutions may be made without departing from the spirit and scope of my invention as set forth in the appended claims. 120

What I claim is:

1. In an apparatus of the character described, a conveyer, means for moving padding material through said conveyer, means arranged to engage a cover to be stuffed 125 when said cover is in position on said conveyer and arranged to yieldingly restrain its motion along said conveyer during the stuffing operation, means arranged to disengage said engaging means from said cover 130

- after said cover has been partially stuffed, and additional means arranged to engage said cover and arranged to yieldingly restrain its motion relatively to said conveyer 5 after the first mentioned means has been disengaged from said cover.
2. In an apparatus of the character described a conveyer for delivering pad stuffing material, clamps for engaging a pad 10 cover to be stuffed, for holding it in position over the conveyer, means connected to the clamps for yieldingly restraining the motion of the cover along the conveyer, means engaged by the clamps during their 15 forward motion along the conveyer, for disengaging the clamps from the cover, and additional clamps for engaging the cover, for holding it in place relatively to the conveyer, and means connected to the additional 20 clamps for yieldingly restraining motion of the cover relatively to the conveyer, after the disengagement of the first mentioned clamps.
3. In an apparatus of the character described, a conveyer, for delivering stuffing material, means for engaging a pad cover to be stuffed and for holding it in position relatively to the conveyer and for yieldingly restraining its motion along the conveyer, additional means for engaging the cover and restraining its motion along the conveyer and automatic means for disengaging the first mentioned means and leaving 35 said additional means operative in restraining the motion of the cover.
4. In an apparatus of the character described, a conveyer for delivering stuffing material, clamps for engaging and holding a cover to be stuffed in position relatively to the conveyer, means for yieldingly restraining relative motion between the clamps and the conveyer during the stuffing operation, a second set of clamps for engaging the cover, means for yieldingly restraining relative motion between the second set of clamps and the conveyer during the stuffing operation, and means for disengaging the first mentioned clamps from the cover after a pre-determined portion of the 45 cover has been stuffed.
5. A machine for stuffing pads, comprising a conveyer for stuffing material, means for forcing the material through the conveyer and into a pad cover to be stuffed, means for holding the cover to be stuffed in position relatively to the conveyer during the stuffing operation, means adapted to render said holding means inoperative after a pre-determined portion of the cover has 55 been stuffed, and additional means for holding the cover in place, after the first mentioned means has been rendered inoperative.
6. A machine for stuffing pads, comprising a conveyer for delivering stuffing material, clamps for engaging and holding a 60 pad to be stuffed in position relatively to the conveyer, means for restraining the motion of the clamps during the stuffing operation and stops engaged by the clamps for releasing them from the cover, in combination with a second set of clamps for engaging the cover and means for restraining the motion of the second set of clamps, which is adapted to be rendered operative after said first mentioned clamps are disengaged from the cover.
7. In a machine for stuffing pads, a conveyer, means located in the conveyer for moving stuffing material therethrough, clamps for engaging a pad cover to be 65 stuffed, and weights for restraining the relative motion between the clamps and the conveyer, in combination with additional clamps for engaging the cover, weights for restraining the motion of the additional 70 clamps, means for disengaging the first-mentioned clamps from the cover, and means for adjusting the position of the last-mentioned weights for rendering them inoperative until after the first-mentioned 75 clamps are disengaged.
8. In a pad stuffing machine, means for delivering pad stuffing material, mechanisms for restraining the relative motion between said means and a pad cover to be 80 stuffed, and means for rendering the mechanisms inoperative during a portion of the stuffing operation.
9. In a pad stuffing machine, means for delivering pad stuffing material, mechanisms 85 for restraining the relative motion between said means and a pad cover to be stuffed, during the stuffing operation, and means dependent on said relative motion for rendering the mechanisms inoperative during a portion of the stuffing operation.
10. In a pad stuffing machine, means for delivering pad stuffing material, mechanisms 90 for restraining the relative motion between said means and a cover to be stuffed during the stuffing operation, means dependent on said motion for rendering said mechanisms inoperative during a portion of the stuffing operation, and additional mechanisms for restraining the relative motion between the first mentioned means and the cover, after said first mentioned mechanisms are rendered inoperative.
11. In a pad stuffing machine, a device for delivering pad stuffing material, means operative during a portion of the stuffing operation for yieldingly restraining the relative motion between the device and a pad cover to be stuffed, additional means for yieldingly restraining the relative motion between the device and the cover after the first mentioned means is inoperative and means engaged by the first-mentioned means, during the stuffing operation, for disengaging said first-mentioned means from the pad cover.

12. In a pad stuffing machine, a device for delivering pad stuffing material, means operative during a portion of the stuffing operation for controlling the relative motion 5 between the device and a pad cover to be stuffed, additional means for controlling the relative motion between the device and the cover during the rest of the stuffing operation, and means for adjusting said additional means so that it is rendered inoperative 10 during the operation of the first mentioned means and operative after the first mentioned means is rendered inoperative.
13. In a pad stuffing machine, a device for 15 delivering pad stuffing material, means operative during a portion of the stuffing operation for controlling the relative motion between the device and a pad cover to be stuffed, automatic means for rendering said first mentioned means inoperative, additional 20 means for controlling the relative motion between the device and the cover during the rest of the stuffing operation, and adjusting means for said additional 25 means for rendering it inoperative during the operation of the first mentioned means and operative after the first mentioned means is rendered inoperative.
14. In a pad stuffing machine, a conveyer 30 for delivering padding material, a plunger for forcing the material through the conveyer and into a cover to be stuffed, a set of clamps for engaging an intermediate portion of the cover and for holding it in place 35 relatively to the conveyer, slideable rods upon which said clamps are mounted, means for yieldingly restraining the motion of said rods, adjustable stops carried by the rods for varying their normal positions, and stops 40 mounted on the frame of the machine for engaging the clamps during the forward motion of the rods and for thereby actuating them to release the cover.
15. In a pad stuffing machine, a conveyer 45 for delivering padding material, a plunger for forcing the material through the con-
- veyer and into a cover to be stuffed, a forward set of clamps for engaging an intermediate portion of a cover and for holding it in place over the conveyer, slideable rods 50 upon which the clamps are mounted, means for yieldingly restraining the motion of the rods, a set of rear clamps for engaging the end portion of the cover, rods upon which the rear set of clamps are mounted, means 55 for restraining the motion of the last mentioned rods, a stop carried by each rod for controlling the normal position of its corresponding clamp, stops mounted on the frame of the machine for engaging the forward 60 clamps and thereby releasing them from the cover during the stuffing operation, and means controlled by the forward motion of one of said rods for stopping said plunger after the cover is stuffed. 65
16. In a pad stuffing machine, a conveyer for delivering padding material, a plunger for forcing the material through the conveyer, means for actuating said plunger, a forward set of clamps for engaging an intermediate portion of a cover to be stuffed, slideable rods upon which said clamps are mounted, weights for restraining the motion of the rods, a rear set of clamps for engaging the end portion of the cover, rods upon 70 which said rear set of clamps are mounted, weights for restraining the motion of the last mentioned rods, stops mounted on the frame of the machine for engaging the forward clamps during the stuffing operation 75 and for disengaging them from the cover, means for adjusting the normal positions of the weights of the rear set of clamps and for rendering them inoperative while the forward clamps are operative, and means 80 controlled by the forward motion of one of said rods for controlling the operation of said plunger actuating means. 85
